RADIATOR CAP

Benjamin H. Bowlus and William Schnell, Detroit, Mich., assignors to Ternstedt Manufacturing Co., Detroit, Mich., a corporation of Michigan

Application April 23, 1931, Serial No. 532,240

12 Claims. (Cl. 220—40)

This invention relates to closure devices such as are commonly provided to close the filling openings of liquid containers such as automobile radiators, gasoline tanks, etc.; and relates more particularly to closure devices of the type wherein a locking bar or equivalent part carried by the closure member is adapted to engage cam surfaces formed on the container filler neck to hold the closure member in position thereon.

Quite frequently such closure devices carry on their exterior surfaces figures or projections which are provided for ornamental or other purposes. Whenever such figures or projections are present on a closure device, it is essential when the closure device is turned to closed position, that the ornamental figure or projection assume the proper position with respect to the adjacent parts in order that a symmetrical appearance may be presented. In practice, when an ornamental figure or projection is used in connection with a closure device of the type wherein a locking bar on the closure member engages cam surfaces formed on the filler neck, shoulder or dwell portions are provided on the cam surfaces, and it is intended that the closure member, when being installed in position to close the opening in the filler neck, shall be turned until the locking bar engages the shoulder or dwell portions, whereupon the ornamental figure or projection is supposed to assume the correct aligned position with respect to the adjacent parts. It has been found, however, that due to unavoidable manufacturing variations, it sometimes happens that certain of the parts of the container or closure device cannot always be assembled in exactly the same relation to other parts, and the result is that when the closure device is turned to closing position with the locking bar engaging the shoulder or dwell portions provided on the cam surfaces of the filler neck, the ornamental figure or projection will sometimes lie in a position where it is not properly aligned with respect to other parts of the vehicle.

It is an object of this invention to correct this condition by so attaching the locking bar or equivalent part to the closure member, that the former may be adjusted to vary to any desired extent its position relative to the closure member, so that when the latter is turned to closed position with the locking bar engaging the shoulder or dwell portions on the cam surfaces of the filler neck, the ornamental figure or projection on its exterior surface will assume a position where it will be correctly aligned with respect to the adjacent parts.

A further object of the invention is to provide means for positively securing the locking bar or equivalent part to the closure member after the former has been adjusted to the proper position to insure correct alignment of the ornamental figure or projection, in order that whenever the closure member is subsequently removed to permit filling of the container and is replaced, the ornamental figure or projection will be certain to be returned to exactly the same position it formerly occupied.

Another object of the invention is to utilize the means which are provided to connect the locking bar or equivalent part to the closure member, to hold a resilient sealing member or members in place on the underside of the closure member, which sealing member is adapted to engage the upper edge of the filler neck when the closure member is assembled in closed position thereon to prevent leakage of the contents of the liquid container.

Other objects and advantages of the invention will be apparent upon referring to the specification and accompanying drawing, in which:

Fig. 1 is a vertical sectional view through a closure device, showing one manner of adjustably connecting a locking bar to a closure member.

Fig. 2 is a view, with parts broken away, showing the underside of the closure device illustrated in Fig. 1.

Fig. 3 is a view corresponding to Fig. 1, but showing a different manner of adjustably connecting the locking bar to the closure member.

Fig. 4 is a sectional view taken on line 4—4 of Fig. 3.

Fig. 5 is a detailed perspective view of one of the parts shown in Figs. 3 and 4.

Fig. 6 is a view corresponding to Fig. 1, but showing another manner of attaching a locking bar to a closure member.

Fig. 7 is a view showing the underside of the closure device illustrated in Fig. 6.

Figs. 8 and 9 are detailed perspective views of parts shown in Figs. 6 and 7.

Fig. 10 is a view similar to Fig. 1, but showing a still different manner of attaching the locking bar to the closure member.

Fig. 11 is a view showing the underside of the closure device illustrated in Fig. 10.

In the drawing the invention is shown as embodied in a radiator cap consisting of a closure member 2 having an ornamental Figure 4 extending from its upper surface. A projection 6 extends downwardly from the underside of the closure member 2, which projection is of circu-

lar shape, but which is provided at its lowermost end with a portion 8 having parallel sides 10, which portion is formed by casting or by cutting away some of the material of the projection 6 at opposite sides thereof which results in the formation of shoulders 11 at opposite sides of the projection. A small circular gasket 12 formed of fiber or other suitable material and having a circular opening provided therein fits 10 over the projection 6 and against the underside of the cap, and a concavo-convex shaped diaphragm 14 formed of spring metal or other suitable material and also having a circular opening formed therein to fit over the projection 6, 15 bears at its center portion against the gasket 12. A large gasket member 16 formed of fiber or other suitable material and having a concavo-convex shape corresponding to that of the diaphragm 14, and also having formed therein a centrally 20 located circular opening adapted to fit over the projection 6, fits against the lower surface of the diaphragm 14. A spacing collar 18 of circular shape fits over the projection 6 and its upper edge bears against the central portion of 25 the gasket member 16.

A locking bar 20 having a circular opening formed therein at its center portion fits over the circular portion of the projection 6, and bears against the spacing collar 18. An adjusting member 26 having formed therein a centrally located elongated opening 28 of rectangular shape, the opposite sides 30 of which are parallel with each other and are spaced slightly further apart than the distance between the parallel sides 10 of the portion 8, fits over the latter and is free to slide back and forth a limited amount crosswise of the cap. A bolt 32 having threaded engagement with the projection 6 serves to hold the parts in assembled position, and a lock washer 34 located between the head of the bolt and the adjusting member 26 serves to prevent loosening of the bolt after the latter has been drawn to tightened position. A pin or projection 36, secured to the locking bar 20 in any suitable manner, passes through a slotted opening 38 formed in the adjusting member 26. Indicating marks 40 are formed on that end of the locking bar 20 which is most remote from the pin 36, and a pointer portion 42 is formed on the adjacent portion of the adjusting member 26.

It will be readily seen that when the bolt 32 is in loosened position the adjusting member 26 may be moved crosswise of the cap on the projection 6 a limited amount, that is, until the 55 ends of the elongated opening 28 abut against the ends of the portion 8, and that due to the pin and slot connection between the adjusting member 26 and the locking bar 20, such sliding movement of the adjusting member will result 60 in rotary or swinging movement of the locking bar on the circular portion of the projection 6, and that as a result of such movement, the position of the locking bar with respect to the cap 2 may be changed to any desired extent with 65 in reasonable limits.

The closure device described above is adapted to be attached to any of the well known types or shapes of filler necks such as that indicated by the numeral 44, wherein portions of the filler neck are bent or otherwise formed to provide cam surfaces 46. When the cap is being placed over the filler neck, the outer ends of the locking bar 20 pass through slots 48 formed in the inwardly and downwardly bent portions of the 75 filler neck, after which rotation of the cap causes

the outer ends of the locking bar to engage the cam surfaces 46 which are so shaped as to draw the cap downwardly thereby causing the gasket member 16 to be tightly compressed against the upper edge of the filler by the spring action of the diaphragm 14. This results not only in bringing about a sealed connection between the cap and the filler neck whereby escape of liquid or vapor is prevented, but the spring action of the diaphragm also serves to hold the cap tightly 10 in closed position.

It is common practice when using closure devices having a locking bar adapted to engage filler neck cam surfaces such as 46, to provide dwell or shoulder portions on the cam surfaces 15 which portions the ends of the locking bar are adapted to engage when the cap is turned to closed position, in order to bring the ornamental figure or other projection on the exterior of the cap into proper aligned position with the adjacent parts, such as the vehicle hood or radiator shell. It has been found, however, that due to variations which are bound to occur during the manufacturing processes, it is impossible to always assemble the various parts in exactly the 20 same relation to each other. For example, the filler neck may be located in one position with respect to one radiator tank while another filler neck due to some slight variation either in manufacture or assembly may be located in slightly 25 different relation to its particular radiator tank. The result is that when the radiator caps are turned to closed position with the ends of the locking bar fitting into the dwell portions or against the shoulder portions on the cam surfaces, the ornamental figures or projections on the tops of the caps will not in all cases set in straight forward position.

By providing a structure such as that illustrated in Fig. 1, if it is found after turning the cap to 40 closed position on the filler neck with the ends of the locking bar 20 fitting into the dwell portions or against the shoulder portions on the cam surfaces 46, that the ornamental Figure 4 or other projection on the cap does not assume 45 exactly the desired position with respect to the radiator shell or other adjacent parts, the bolt 32 may be loosened and the adjusting member 26 moved sidewise on the projection 8, thereby causing the locking bar 20 to be swung to a different position with respect to the cap 2, after which the bolt 32 may be tightened again to positively hold the parts in adjusted position, since when the bolt is tightened the adjusting member is clamped tightly between the shoulders 11 and 55 the lock washer 34 and is thereby prevented from moving by this clamping action and since the locking bar 20 is positively connected to the adjusting member by the pin 36, the locking bar is also prevented from moving relative to the cap 60 until the bolt 32 is again loosened. It may be found necessary to try the cap on the filler neck several times, and to adjust the position of the locking bar relative to the cap to several different positions before the correct relation of 65 the parts will be obtained, but after this has been once determined, and the parts are locked in the correctly adjusted position by tightening the bolt 32, no further change will ever be necessary and the ornamental figure or other projection on the 70 exterior of the cap will always be bound to assume the proper aligned position with respect to adjacent parts whenever the cap is turned to closed position.

While the locking bar 20 is being moved rela- 75

tive to the cap 2 to determine what is the correct relation of the parts, the position of the pointer portion 42 with respect to the indicating marks 40 may be observed to indicate how much change 5 has been made in the position of the locking bar 20 relative to the cap 2. With the form of adjusting mechanism described above, it will be readily seen that the position of the locking bar 20 relative to the cap 2 may be varied to 10 any desired extent from a fraction of a degree to several degrees. Since no interengaging projections or grooves are depended upon to hold the parts in adjusted position, the locking bar may be set to an infinite number of positions with 15 respect to the cap, and the exact desired position of the ornamental figure or projection may be obtained.

In the form of the invention illustrated in Figs. 3 to 5 the closure member 50 is provided with a 20 projection 52 which extends downwardly from its under surface. The outer surface of the projection 52 tapers slightly and the projection is of greatest diameter at the point where it is joined to the cap. Serrations or pointed projections 54 25 are formed on the outside surface of the projection 52 as is shown in Fig. 4. An adjusting member 56, shown in Fig. 5, having a tapered opening 58 formed therein which tapered opening corresponds generally to the shape of the tapered projection 52, fits over the latter. A groove 60 30 is formed across the under surface of the adjusting member 56 and a locking bar 62 fits into this groove and is held therein by means of a bolt, 64 which passes through central openings formed 35 in the locking bar and the adjusting member 56, and is threaded into engagement with the cap 50. A spring metal concavo-convex shaped diaphragm 66 having formed therein a central opening adapted to fit over the projection 52 bears 40 at its central portion against the under surface of the cap 50, and a gasket member 68, formed of fiber or other suitable material of concavo-convex shape and provided with a central opening adapted to fit over the projection 52, fits against 45 the underside of the diaphragm 66. Both the diaphragm 66 and the gasket member 68 are held in position by the adjusting member 56, the upper edge of which bears against the central portion of the gasket member 68.

Should it be found necessary to change the 50 position of the locking bar 62 relative to the cap 50 in order to properly align an ornamental figure or projection which might be carried by the cap 50, the bolt 64 would first be loosened. It would 55 then be possible to rotate the adjusting member 56 on the projection 52 and since the locking bar 62 is secured in the groove 60 in the adjusting member 56, the locking bar will move with the adjusting member. After the correct relation of 60 the locking bar with respect to the cap has been determined, the bolt 64 may be tightened thereby causing the adjusting member 56 to be drawn into wedging engagement with the tapered projection 52, and the serrations or pointed projections 54 will be caused to cut into the surface of the tapered opening 58 in the adjusting member 56, thereby insuring that there will be no relative rotation between the adjusting member 56 and the projection 52 until the bolt 64 is again 65 loosened.

In Figs. 6 to 9 another form of the invention 70 is illustrated. The cap member 70 is provided with a projection 72 which extends downwardly from its under surface. The outside surface of 75 the projection 72 is circular in shape and is of

uniform diameter, and a tapered opening 74 is formed in the center of the projection. A locking bar 76, shown in Fig. 8, is provided with upwardly extending pointed portions 78 which converge toward each other at their upper ends, and these pointed portions conform generally in shape to the shape of the tapered opening 74 in which they are adapted to fit. A tapered wedging or expanding member 80, shown in Fig. 9, and having serrations or pointed projections 82 formed thereon, fits inside the pointed portions 78, and is adapted to be drawn into engagement with the latter by means of a bolt 84 which is threaded into the cap 70. A spring metal diaphragm 86 of concavo-convex shape and having a central opening formed therein adapted to fit over the projection 72 bears at its central portion against a gasket 88 of circular shape, which in turn bears against the under surface of the cap 70. A gasket member 90 formed of fiber or other suitable material and of concavo-convex shape has formed therein a central opening adapted to fit over the projection 72, and is held in place against the under surface of the diaphragm 86 by means of a spacing collar 92 which surrounds the projection 72 and is in turn held in place by means of the locking bar 76.

With this construction, should it be found necessary to change the position of the locking bar relative to the cap to bring an ornamental figure or projection carried by the cap into proper aligned position, the bolt 84 is loosened and the tapered portions 78 formed on the locking bar may then be rotated inside the tapered opening 74 to permit the locking bar to be set in the desired relation to the cap. When this relation has been established, the bolt 84 is tightened, thereby forcing the wedging member 80 into engagement with the tapered finger portions 78 which results in the latter being expanded into firm contact 30 with the wall of the tapered opening 74 thereby preventing relative rotation of the locking bar 78 with respect to the cap until the bolt 84 is again loosened. Due to the engagement of the serrations or pointed projections 82 on the member 80 35 with the tapered finger portions 78 during the tightening action of the bolt 84, rotation of the wedging member 80 is prevented, thereby permitting the proper action of the lock washer 94, 40 which serves to prevent loosening of the bolt 84. 50

In Figs. 10 and 11 a still different form of the invention is illustrated. In this construction, the cap 100 has formed on its under surface a circular recess 102, in which is received an adjusting member 104, at the outer edges of which are 55 provided pointed projections 106 which are adapted to fit into correspondingly shaped notches 108 formed in the outer edge 103 of the recess 102. A locking bar 110 is held against the under surface of the adjusting member 104 by means of a screw 112 which is threaded into engagement with the cap. Projections 114 bent up from the adjusting member fit into openings 116 formed in the locking bar to prevent relative rotation between the locking bar and the adjusting member. A resilient gasket 118 of any suitable material adapted to engage the top of the filler neck is held in the cap.

In this form of the invention, when it is desired to move the locking bar 104 relative to the cap 70, the screw 112 is loosened enough so that the adjusting member 104 may be withdrawn from the recess 102 after which the pointed projections 106 may be placed in other of the notches 108, and when the desired relation of the locking 75

bar and the cap has been obtained, the screw 112 may be tightened, whereupon there can be no relative movement of the locking bar with respect to the cap because of the engagement of the 5 projections 114 in the openings 116 of the locking bar.

From the above it will be readily seen that our invention contemplates many simple and inexpensive forms of closure devices, wherein the position of the locking bar with respect to the cap may be easily and quickly changed, and wherein after the desired relation has been determined, the parts may be locked positively in that relation without the possibility of there being any 10 subsequent change in the relation of the parts unless desired.

It is thought from the foregoing taken in connection with the accompanying drawing, that the construction and operation of the device will 20 be apparent to those skilled in the art, and that various changes in size, shape and proportion and details of construction may be made without departing from the spirit and scope of the appended claims.

25. We claim:

1. A closure device comprising a cap member, a locking bar rotatably supported on said cap member, an adjusting member slidably mounted on said cap member, and means connecting said 30 locking bar with said adjusting member whereby sliding movement of the adjusting member causes rotative movement of the locking bar relative to said cap member.

2. A closure device comprising a cap member, a locking bar rotatably supported on said cap member, an adjusting member slidably mounted on said cap member, means connecting said locking bar with said adjusting member whereby 35 sliding movement of the adjusting member causes rotative movement of the locking bar relative to said cap member, and means adapted to secure the locking bar in adjusted position.

3. A closure device comprising a cap member having a projection depending from its underside, 45 said projection being provided with a circular portion and a portion having parallel sides, a locking bar rotatably mounted on said circular portion, an adjusting member slidably mounted on said parallel sided portion, and means connecting said locking bar with said adjusting member whereby sliding movement of the adjusting member causes rotative movement of said locking bar relative to said cap member.

4. A closure device comprising a cap member having a projection depending from its underside, 55 said projection being provided with a circular portion and a portion having parallel sides, a locking bar rotatably mounted on said circular portion, an adjusting member slidably mounted on said parallel sided portion, means connecting said locking bar with said adjusting member in such manner that sliding movement of the adjusting member causes rotative movement of the locking bar relative to the cap member, and means adapted to secure the locking bar in adjusted position.

5. A closure device comprising a cap member having a projection depending from its underside, 70 said projection being provided with a circular portion and a portion having parallel sides, a locking bar rotatably mounted on said circular portion, an adjusting member slidably mounted on said parallel sided portion, and a pin and slot connection between said locking bar and said 75 adjusting member whereby sliding movement of

the adjusting member causes rotative movement of the locking bar relative to the cap member.

6. A closure device comprising a cap member having a projection depending from its underside, 5 said projection being provided with a circular portion and a portion having parallel sides, a locking bar rotatably mounted on said circular portion, an adjusting member slidably mounted on said parallel sided portion, means connecting said locking bar with said adjusting member in such manner that sliding movement of the adjusting member causes rotative movement of the locking bar relative to the cap member said locking bar being provided with indicating marks and said adjusting member carrying a pointer which cooperates with said marks to indicate the position of the locking bar relative to the cap member. 10

7. A closure device comprising a cap member having a projection depending from its underside with an opening formed in said projection, a locking bar having a central portion adapted to be rotatably received in said opening, and wedging means adapted to force said central portion of the locking bar into engagement with the wall of said opening whereby the locking bar will be 25 firmly held in adjusted position relative to said cap member.

8. A closure device comprising a cap member having a projection depending from its underside, 30 said projection having a tapered opening formed therein, a locking bar having a tapered portion adapted to be rotatably received in said tapered opening, a tapered member adapted to fit inside the tapered portion of said locking bar, and means adapted to force said tapered member 35 into the tapered portion of the locking bar whereby said tapered portion is expanded into engagement with the wall of said tapered opening thereby causing the locking bar to be firmly held in adjusted position relative to said member. 40

9. A closure device comprising a cap member having a projection depending from its underside, said projection being provided with a circular portion and a non-circular portion, a locking element rotatably mounted on said circular portion, an adjusting member slidably mounted on said non-circular portion, and means connecting said locking bar with said adjusting member whereby sliding movement of the adjusting member causes rotative movement of 45 said locking bar relative to said cap member.

10. In a closure for containers having a filler spout provided with locking members, a cap having a projection depending from its under surface, a resilient sealing disc having an opening 55 formed therein through which said projection extends, said disc being adapted to resiliently engage said filler spout in sealing relationship when the cap is secured to the filler spout, a sleeve extending around said projection and adapted to engage said disc, a locking element having portions adapted to engage said locking members to secure said cap to said filler spout, said locking element being rotatably supported on said projection and being adapted to engage said 60 sleeve for the purpose of holding said disc in position upon said projection, and means adapted to hold said locking element in position upon said projection and in engagement with said sleeve, said means also being adapted to positively hold 65 said locking element in adjusted position relative to said cap.

11. A closure device comprising a cap member having a projection depending therefrom, said projection having a circular surface formed 75

thereon, a resilient sealing disc having an opening formed therein through which said projection extends; a locking member having a circular surface formed thereon, the circular surface on said locking member being adapted to bear against the circular surface on said projection, and means associated with said projection adapted to lock said locking member in any desired position relative to said cap member, said means also serving to hold said resilient sealing disc in position upon said projection.

12. A closure device comprising a cap mem-

ber having a projection depending therefrom, said projection having a circular surface formed thereon, a locking member having a circular surface adapted to engage the circular surface on the projection whereby the locking member will be rotatably supported on the projection, and means secured to said projection adapted to lock said locking member in any desired position relative to said cap member.
